United States Patent Office

Des. 208,301
Patented Aug. 15, 1967

208,301

CHAIR

Dorothy D. Richards, Clayton, Mo.
(710 S. Hanley Road, St. Louis, Mo. 63105)

Filed Oct. 17, 1966, Ser. No. 4,294

Term of patent 3½ years

(Cl. D15—1)

FIGURE 1 is an isometric view of a chair, showing my new design; and

FIGURE 2 is a rear elevational view thereof, on a reduced scale.

I claim:

The ornamental design for a chair, substantially as shown.
